UNITED STATES PATENT OFFICE

2,514,100

DISHWASHER

William R. Spaulding, Kansas City, Mo.

Application November 13, 1945, Serial No. 628,269

1 Claim. (Cl. 134—177)

1

This invention relates to household appliances of the character commonly referred to as dishwashers and has for its primary aim to provide such equipment as embodies novel and unique means for directing water or cleansing fluid against the articles being washed; structure for driving a specially formed water-scoop that is capable of serving as an air motivating element; and a reservoir for supplying water and detergent to the articles being cleaned.

Other aims of the invention are to provide a dish washer having a specially disposed drain through the medium whereof the wash water may be emptied into a kitchen sink and a reservoir mounted to direct streams of water downwardly through the articles being cleaned as the water-scoop, forming a part of the equipment, forces volumes of water upwardly against the said articles.

Other aims of the invention will appear during the course of the following specification and referring to the accompanying drawing, wherein:

Fig. 1 is a top plan view of a dish washer made in accordance with the present invention.

Fig. 2 is a side elevational view thereof with parts broken away for clearness.

Fig. 3 is a plan view of the water-scoop entirely removed from association with the remaining parts of the machine, and

Fig. 4 is a fragmentary detailed sectional view on an enlarged scale taken on line IV—IV of Fig. 3 and looking in the direction of the arrows.

Dish washers have heretofore been used but their complicated character has precluded universal employment particularly in homes where domestic dish-washing should be done without the necessity of operating involved mechanical parts.

The dish washer made in accordance with my invention is inexpensive to produce, easy to operate, efficient in action and capable of cleansing the dishes to a point where they are dry and ready for re-use.

In the embodiment of the equipment chosen for illustration the dish washer comprises a tank 10 formed of sheet metal and having a rack 12 therein. This rack is designed to support dishes or other articles to be washed and the same may be made of wire for the purpose of insuring uninterrupted passage of water from the overlying reservoir 14 and from the water-scoop 16 which is disposed below rack 12. Rack 12 is removably seated in tank 10 upon supports 18 and these supports hold the bottom of rack 12 well above water-scoop 16 that is rotatably carried

5 by a shaft 20 driven by motor 22 through the medium of a belt 24. This motor 22 is housed within a case 26 forming a support for tank 10 and having wheels 28 to lend mobility to the entire assembly.

Water-scoop 16 is of the form shown in Figs. 3 and 4 and comprises a plurality of substantially radial blades 30, each of which is inclined, as shown in Fig. 4, to force fluids upwardly 10 through tank 10. When water or cleaning fluid is within tank 10, scoop 16 lifts the water upwardly through rack 12 and against the dishes or other articles. As this is being done, water with suitable detergent therein is dropping downwardly on to the dishes or articles in rack 12 through perforations 32 formed through the bottom of reservoir 14. This reservoir 14 is of a special character in that it is a lid or cover for the top of tank 10 and is hinged at 34 for movement to and from the closed position. A filler opening 36 having a cover 38 is employed when water is to be emptied into reservoir 14.

From the above it will be apparent that counterflow is established within tank 10 by water falling through perforations 32 and by additional water being directed upwardly against the bottom of reservoir 14 having perforations therein, by scoop 16.

25 A drain tube 40 having connection with the interior of tank 10 near the bottom thereof and as clearly shown in Fig. 2, is shiftable from a position where the open end thereof is above the normal level of water within tank 10 to a place where the water may flow from this tank and into a sink or other drain. When all of the water has been removed from tank 10 through drain tube 40, reservoir 14 may be lifted from the closed position and scoop 16 rotated at a high rate of speed to force air upwardly through all of the articles in rack 12 which have been washed and made ready for further use. This air will dry the said articles without removing them from rack 12.

The dish washer is constructed to present a 40 neat appearance and when manipulating the same, handle 42 is utilized to draw the machine from place to place and particularly from dining table to kitchen where the dishes are collected and later washed near the sink. The washer is, therefore, in the character of a quickly movable cart. When water is emptied into reservoir 14, such soap or other detergent as may be needed, is mixed therewith and a thorough cleansing of the articles in tank 12 is insured.

50 It is realized that dish washers having physical

characteristics different from those shown and described may be made without departing from the spirit of the invention or scope of the appended claim.

Having thus described the invention what I claim as new and desire to secure by Letters Patent is:

A dish washer comprising a hollow open top tank capable of receiving a quantity of cleansing fluid; a reservoir movable to and from a position closing said open top of the tank; a bottom wall forming a part of said reservoir and completely covering said tank when the reservoir is in said position; a cup-shaped dish-receiving, foraminous basket in the tank, said basket being disposed below said reservoir bottom and spaced above the bottom of the tank, the cross-sectional areas of the tank and of the basket being substantially the same; and a rotatable scoop in the tank below the basket capable, when rotating, of directing cleansing fluid upwardly through the basket, against the dishes in the basket and

against said bottom of the reservoir, said reservoir bottom being provided with a plurality of perforations for receiving some of the fluid being directed upwardly by the scoop, said perforations all being unrestricted whereby to permit free flow of said fluid passing therethrough into the reservoir and free downward return thereof through the perforations by force of gravity from the reservoir, into the tank and upon the dishes in said basket.
